CLAIM

The ornamental design for a trimming and deburring tool for gun cartridge cases, as shown and described.

DESCRIPTION

FIG. 1 is a perspective view of a trimming and deburring tool for gun cartridge cases showing my new design;

FIG. 2 is a top plan view thereof;

FIG. 3 is a bottom plan view thereof;

FIG. 4 is a side elevational view thereof; and

FIG. 5 is a side elevational view thereof rotated 45° from the view shown in FIG. 4.

Fig. 1.

Fig. 2.

Fig. 3.

Fig. 4.

Fig. 5.
